UNITED STATES PATENT OFFICE

2,273,773

SLIDE FASTENER

Noel J. Poux, Meadville, Pa., assignor to Talon,
Inc., a corporation of Pennsylvania

Application July 29, 1940, Serial No. 348,116

5 Claims. (Cl. 24—205.5)

My invention relates to slide fasteners and more particularly to separable end connections therefor.

In general, the objects of my invention are to provide a separable end connection for slide fasteners, which is especially suitable for slide fasteners of plastic materials; to make the parts of the separable end fitting simple and easy to manufacture and yet durable; and to provide an improved reinforcing connection between the separable end parts and the tapes of the slide fastener.

Other objects and advantages of the invention will hereinafter more fully appear.

In the accompanying drawing, I have shown, for purposes of illustration, one embodiment which my invention may assume in practice. In the drawing:

Fig. 1 is a face view of a slide fastener including my improved separable end fitting.

Fig. 2 is a central section through the separable end fastener, indicating the position of the parts during assembly;

Fig. 3 is a similar view on somewhat larger scale, showing the parts almost fully assembled;

Fig. 4 is a corresponding view showing the parts fully assembled and the slider moved partly toward closed position of the fastener;

Fig. 5 is a cross section on the line 5—5 of Fig. 1;

Fig. 6 is a perspective view, partly broken away, showing the socket side of the separable end connection;

Fig. 7 is a perspective view showing the pin side;

Fig. 8 is a longitudinal cross section on the line 8—8 of Fig. 7; and

Fig. 9 is a section taken substantially on the line 9—9 of Fig. 3 and illustrating the cooperation of the locking detent of the slider with the socket side of the separable end connection.

In general, the slide fastener, with which I have shown my improvement associated, is of a familiar type which consists of tapes 9, 10, having attached to their adjacent edges, fastener members 11 of plastic material. A slider generally designated 12 is mounted on the rows of fastener members for engaging and disengaging them as it is moved from one end of the fastener to the other. This slider is preferably of oval shape having a rounded forward end 13 and it is provided with suitable means for moving it by hand, such as a bail 14 and pull tab 15. The slider body is molded and carries a known type of spring locking device 16 which has a locking

prong 17 that will spring into engagement between the fastener elements and hold the slider until it is manually moved by the pull tab 15.

The separable bottom connection comprises generally a socket or retainer element 18 attached to the end of tape 9 beyond the end of the row of fastener members on that tape and a mating pin member 19 attached to the tape 10. As is usual in slide fasteners with separable end connections on the market today, the pin is adapted to be threaded through the slider and into engagement with the socket.

It will be understood that the entire socket member is formed preferably in one piece which can be conveniently accomplished by a molding operation. It consists principally of a box-shaped portion 20 which may be provided with suitable ornamentation, and the sides and bottom of which may have any desired configuration. This member has a closed bottom and a channel 21 which opens at the top and which is large enough to receive the pin member 19. This channel opens up through the side of the socket member by way of a narrow slot so that the tape of the pin member can slide through the slot.

To secure the box-shaped member to the tape, it is overlapped with the edge of the tape and has integral side elements 22 which extend further over the tape. Preferably also the tape is folded back, as indicated at 23, so as to reinforce the end of the tape. The wings or extensions 22 are necessarily very thin and, when made of plastic material, are, to certain extent, flexible. These extensions constitute an integral part of the box-shaped member and thereby greatly reinforce the holding power on the tape. Between the box-shaped portion and the end-most fastener member, there is a tubular extension 24 which is necessary to allow separation of the stringers when the slider is moved against the box-shaped member. The wings or extensions 22 preferably extend upwardly along at least part of the length of this tubular member and are cut on an incline corresponding to the incline of the folded-over portion of the tape. It will be observed that the upper edge of the box-shaped member, on both sides of the tape, is concavely curved to form a nest or seat for the rounded end of the slider.

The pin member 19 has extensions or wings 25 corresponding to those marked 22 on the opposite stringer, and these are preferably integral with the material of the pin 19 so that they will greatly help in holding the pin in place on the end of the tape. The pin thus has shoulders 26

which cooperate with corresponding shoulders 27 on the socket member to resist lateral separation after the pin has been threaded into the socket. This pin, near the bottom end, has on opposite sides of the tape, notches 28 forming, in effect, hooks 29 which engage in corresponding recesses or holes 30 in the socket member, as seen very well in Fig. 4. This prevents endwise slipping movement of the pin relative to the socket after they have been assembled and greatly tends to eliminate what would otherwise be a source of trouble, especially in fasteners of plastic material.

The front face of the pin is formed with a groove 31 which fits over a correspondingly shaped rib 32 on the face of the tubular extension 24 and inner wall of the socket member. This effectively prevents sidewise shifting movement of the pin after it has been assembled in the socket.

Another very desirable feature, as seen especially in Fig. 4, is the bevelling off of the pin member at 33 and the corresponding bevelling off of the tubular extension 24, as indicated at 34, to allow freer flexing of the stringer relative to the parts of the end connection, thereby tending to avoid breakage of the fabric tapes at these points.

The manner in which the integral wing extensions on the pin and socket help to reinforce the tapes and hold the pin and socket to the tapes may be seen in Fig. 8, where the material of these wings is shown as penetrating through preformed openings 35 in the tape and this material also may penetrate the spaces between the threads of the tape and even flow between the tapes themselves, as shown in this figure to an exaggerated degree.

It is very desirable when the pin is separated from the socket that the slider be held in proper position for reassembly. To accomplish this purpose, I take advantage of the usual locking device 16 and pin 17 by providing a recess 36 in the tubular extension 24 to receive the lock pin when the slider is moved against the box-shaped portion of the socket member.

The operation of my improved device will be readily understood. The pin is inserted through the channel of the slider, as shown in Fig. 2, at a slight angle to the other stringer. When it is fully inserted, as shown in Fig. 3, the slider is then pulled up, whereupon the tape stringers will tend to straighten up the parts and swing the hook element 29 into the socket 30, as shown in Fig. 4, so as to hold the parts together very firmly. The parts may be disconnected by simply reversing this procedure.

It is, of course, to be understood that the above description is merely illustrative and in nowise limiting and that I desire to comprehend within my invention such modifications as are included within the scope of the appended claims.

Having thus fully described my invention, what I claim as new and desire to secure by Letters Patent is:

1. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, and a separable end connection comprising a socket member attached to one of the projecting tape ends adjacent the row of fastener members on that tape, a pin member

secured to the projecting tape end of the other stringer adapted to be threaded into engagement with the socket member, and thin wings extending laterally from the socket member and from the pin member in overlapping relation with the tape, said wing extensions being integral with the material of the socket member and pin member respectively and being firmly secured to the underlying portions of the tape.

5 2. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, and a separable end connection comprising a socket member attached to one of the projecting tape ends adjacent to the row of fastener members on that tape, a pin member 10 secured to the projecting tape end of the other stringer adapted to be threaded into engagement with the socket member, said pin and socket member being formed of plastic material, and thin wing extensions integral with the pin and socket members and formed of the same material, said wing extensions projecting laterally on opposite sides of the tape from pin and socket members and being adhesively secured to the tapes.

15 3. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, a separable end connection comprising a socket member attached to one of the projecting tape ends adjacent the row of fastener members on that tape, a pin member 20 secured to the projecting tape end of the other stringer adapted to be threaded into engagement with the socket member, said pin and socket member being formed of plastic material, and thin wing extensions integral with the pin and socket members and formed of the same material, said wing extensions projecting laterally on opposite sides of the tape from pin and socket members and being adhesively secured to the tapes.

25 4. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, a separable end connection comprising a socket member attached to one of the projecting tape ends adjacent the row of fastener members on that tape, a pin member 25 secured to the projecting tape end of the other stringer adapted to be threaded into engagement with the socket member, said pin and socket member being formed of plastic material, and thin wing extensions integral with the pin and socket members and formed of the same material, said wing extensions projecting laterally on opposite sides of the tape from pin and socket members and being adhesively secured to the tapes.

30 5. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, a separable end connection comprising a socket member attached to one of the projecting tape ends adjacent the row of fastener members on that tape, a pin member 30 secured to the projecting tape end of the other stringer adapted to be threaded into engagement with the socket member, said socket member having a hollow box-shaped portion spaced from the fastener members and a tubular portion extending to the fastener members, said tubular extension and said pin member at their ends adjacent the endmost fastener member on the stringer, being beveled to provide clearance for easy flexing of the tapes between the parts of 35 the separable end connection and the fastener members, and thin integral wing extensions on said tubular portion and said wing member projecting laterally therefrom on opposite sides of the tape, the upper ends of said wing extensions having bevels corresponding with the bevels on said tubular extension and said pin member respectively.

40 6. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, and a separable end connection comprising a socket member attached to one of the projecting tape ends adjacent the row of fastener members on that tape, a pin member 40 secured to the projecting tape end of the other stringer adapted to be threaded into engagement with the socket member, the projecting ends of said tape being folded under and cut on an incline, and lateral extensions from said pin and socket members extending laterally therefrom over the folded under portion of the tape, the

top edge of the extensions having the same incline as the folded ends of the tapes.

5. A slider fastener comprising a pair of tapes, rows of fastener members attached to the adjacent edges of the tapes, a slider mounted on the rows of fastener members for engaging and disengaging them, the tapes projecting beyond the rows of fastener members at the bottom end of the fastener, and a separable end connection comprising a socket member attached to one of the projecting tape ends adjacent the row of fastener members on that tape, a pin member secured to the projecting tape end of the other stringer adapted to be threaded into engagement

with the socket member, said slider having a locking device including a locking detent movable inwardly and outwardly relative to the fastener members, said socket member having a box-shaped portion against which the slider abuts when the fastener is open and a tubular extension between the box-shaped member and the fastener members over which the slider is moved when the fastener is open, said tubular extension having a recess into which said locking detent may engage to hold the slider in position against the box-shaped member while the pin member is disconnected therefrom.
